UNITED STATES PATENT OFFICE.

GEORGE KESSLER, OF NEW YORK, N. Y., ASSIGNOR TO THE TUTTLE & BAILEY MANUFACTURING COMPANY, OF SAME PLACE.

DESIGN FOR A SMOKE-PIPE REGISTER.

SPECIFICATION forming part of Design No. 33,696, dated December 11, 1900.

Application filed November 15, 1900. Serial No. 36,645. Term of patent 14 years.

To all whom it may concern:

Be it known that I, GEORGE KESSLER, a citizen of the United States, and a resident of the city of New York, borough of Brooklyn, in the county of Kings and State of New York, have invented and produced a new and original Design for a Smoke-Pipe Register, of which the following is a full, clear, and exact description.

Reference is to be had to the accompanying drawings, forming a part of this specification, in which similar characters of reference indicate corresponding parts in both the views.

Figure 1 is a face view of a smoke-pipe register, showing my design; and Fig. 2 is a sectional side elevation of the same on the line 2 2 in Fig. 1.

The design in its entirety consists of a solid circular rim A, ornamented on the top by raised figures B and appearing joined at the inner edge by open-work C with a solid ring D, in which appears the open-work centerpiece E, the said rim A, open-work C, and

ring D appearing concentric, the centerpiece being arched at the middle, as is plainly indicated in Fig. 2, and the under side of the register appearing with concentric depending flanges F and G at the rim A and the ring D, respectively.

The leading feature of the design consists of the rim joined by the open-work C with the solid ring D and the centerpiece E appearing set in the ring D.

Having thus fully described my invention, I claim as new and desire to secure by Letters Patent—

The design for the smoke-pipe register herein shown and described.

In testimony whereof I have signed my name to this specification in the presence of two subscribing witnesses.

GEORGE KESSLER.
